United States Patent Office.

ORVILLE MANLY, OF GARRETTSVILLE, OHIO.

Letters Patent No. 72,060, dated December 10, 1867.

IMPROVED ROOFING.

The Schedule referred to in these Letters Patent and making part of the same.

TO ALL WHOM IT MAY CONCERN:

Be it known that I, ORVILLE MANLY, of Garrettsville, in the county of Portage, and State of Ohio, have invented a new and improved Roofing; and I do hereby declare that the following is a full, clear, and exact description thereof, which will enable those skilled in the art to make and use the same, reference being had to the accompanying drawings, forming part of this specification.

This invention relates to a new and improved method of constructing the roofs of buildings, whereby the same are more durable and more economically made.

It consists of tiles saturated with raw coal-tar, made in the same way as ordinary brick, having all the edges bevelled, being thicker at one end, and laid upon the roof with the thinner end towards the eaves, and the spaces between the tiles, formed by the bevelled sides of the same, filled with a cement made of raw coal-tar and clay. In the accompanying plate of drawings—

Figure 1 represents a plan view of a roof with the tiles laid.

Figure 2 represents a longitudinal section of the same, taken in the line *x x*, fig. 1, showing the spaces made by the bevelled sides of the tiles.

Figure 3 is a cross-section of the same, taken in the line *y y*, fig. 1, showing the spaces made by the bevelled ends of the tiles.

Figure 4 is a plan view of one of the lower row of tiles, forming the trough.

Figure 5 represents a longitudinal section of the same.

Similar letters of reference indicate corresponding parts.

The roof *A* is made in the usual way, of boards laid closely together, either covered with felting or not. The tiles *a* are made of any convenient size, of the same material and in the same way as common bricks, having all their edges bevelled, as shown in the drawing, fig. 4, and are made thicker at one end than the other, so as to leave a projection or elevation, as represented at *e*, fig. 5. The sides and ends are bevelled, so that the tiles *a* are broader and longer on the lower or under side, so that when laid together the spaces *S* are left between said tiles *a* to receive the cement. The tiles *a* are saturated with raw coal-tar, which they readily absorb, so that said tiles *a* are rendered completely impervious to water. Said tiles *a* are made thicker at one end, so as to leave an elevated projection, which on an inclined or slanting roof prevents the cement, when warm, from running down to the eaves. Said tiles *a* are laid upon the boards or felting of the roof, with the thinner end towards the eaves, as represented in the drawing, fig. 3, in the same way as bricks are laid in building, so that the joints are broken, as represented in the drawing, fig. 1.

The tiles *b*, of which the lower row of tiles is made, are formed by a flange on the lower end, at right angles to the body of the tile, the space between the flange and the body of the tile being partly filled, so as, when they are laid together, said tiles form a spout or trough, as represented in the drawing, figs. 3, 4, and 5. Said tiles *b* have two or more of their sides bevelled, in the same manner as the tiles *a*. Said tiles *b* are used along the sides of the roof and along the edge, where they constitute an eaves-trough, as shown in the drawing, within and not projecting beyond the roof. Said tiles *b* are made of the same material, in the same way, and are in like manner saturated with coal-tar, as the tiles *a*. The cement with which the spaces *S* are filled is made of pulverized blue clay and raw coal-tar, in about the proportion of eighty or one hundred pounds of the clay to four gallons of coal-tar, or in such proportions of the said materials as shall make the mass of proper consistency to be easily worked, and may be used for filling up spaces between the tiles, or generally for making roofs either water or fire-proof.

The saturated tiles *a* and the saturated tiles *b*, having the spaces *S* between them laid and filled with the cement, as above described, constitute a cheap water and fire-proof roof, free from the objections to the cement and tile-roofs for buildings now commonly in use.

I claim as new, and desire to secure by Letters Patent—

1. A roof, composed of tiles *a* and *b*, having spaces *S* between them for a water-tight cement, substantially as shown and described, and for the purposes set forth.

2. The saturated tiles *a* and the saturated tiles *b*, substantially as shown and described, and for the purposes set forth.

3. The lower or outer row of tiles *b*, when laid together, forming an eaves-trough, substantially as shown and described, and for the purpose set forth.

The above specification of my invention signed by me, this 30th day of September, 1867.

ORVILLE MANLY.
